UNITED STATES PATENT OFFICE.

OTTO C. SCHULZ, OF CHICAGO, ILLINOIS, ASSIGNOR TO BAUER & BLACK, OF CHICAGO, ILLINOIS, A CORPORATION OF ILLINOIS.

FIRST-AID PACKET OR PACKAGE.

1,234,397.

Specification of Letters Patent.

Patented July 24, 1917.

Application filed April 24, 1916. Serial No. 93,107.

To all whom it may concern:

Be it known that I, OTTO C. SCHULZ, a citizen of the United States, residing at Chicago, in the county of Cook and State 5 of Illinois, have invented certain new and useful Improvements in First-Aid Packets or Packages, of which the following is a specification.

It has heretofore been the practice to furnish individual soldiers in the army with a sealed container in which a pair of bandages are arranged, with which a wounded soldier may bind his wound to stop the flow of blood and prevent infection. Recent developments 15 in military surgery have indicated that a larger proportion of wounds can be healed if immediately treated with a solution of iodin. Inasmuch as the container is of standard dimensions, being designed to receive only the bandages above referred to, a difficult problem of including the iodin within 20 in the container is presented.

It is the object of my invention to provide a standard first aid packet or package 25 comprising a pair of bandages tightly packed in a sealed container, with one or more ampoules or swabs containing iodin or other cleansing, disinfecting or healing liquid, without increasing the size of the packet or package, and also to arrange the ampoules or swabs within the packet or package so that they will be protected by the bandages in assembling the packet or package and in handling the same.

30 Other objects and advantages of my invention will be apparent as it is better understood by reference to the following specification when read in connection with the accompanying drawing, illustrating the preferred embodiment thereof, in which—

Figure 1 is a view in perspective of the container, partially broken away to show the contents of the packet or package;

Fig. 2 is a view in perspective of a pair 45 of bandages with the complementary depressions to receive the iodin swabs;

Fig. 3 is a view in perspective of an iodin swab;

Fig. 4 is a section on the line 4—4 of Fig. 50 1, and

Fig. 5 is a view in perspective of a single bandage with the swabs assembled therewith.

Referring to the drawing, 1 indicates a 55 suitable metal container of standard dimen-

sions adapted to be sealed to prevent infection of the contents and to be readily opened when required. Two bandages 2 have heretofore been sterilized, compressed and tightly packed within the container, the latter being 60 made of a size just sufficient to hold the bandages when packed snugly therein. To accommodate a pair of iodin swabs within the container without injuring the container and without reducing the size of the bandages or mutilating the same I subject each bandage to pressure in a compress (not shown) which is adapted to produce one or more depressions 3 in one face of the bandage, the depressions being located so that 70 when the two bandages are arranged face to face within the container they will form openings adapted to receive the swabs.

The swabs are preferably of the type described in my copending application, Serial 75 No. 93,106 filed April 24, 1916, consisting of a glass container 5 inclosed within a fabric wrapper 6 which extends beyond the glass container to form an applying means 7. By breaking a restricted neck portion of 80 the glass container the contents is allowed to flow to the applying means.

Before placing the bandages 2 within the container 1 they are wrapped preferably in paper 8 which is sufficiently loose to allow it 85 to be forced into the depressions 3. A plurality of safety pins in a suitable wrapper 9 are preferably disposed between the bandages 2. The parts being assembled, the container 1 is sealed.

90 My invention provides for including in a first aid packet or package of standard size one or more swabs or ampoules for first aid use without increasing the size of the packet or package, without decreasing the 95 size of the bandages and without mutilating the bandages. Furthermore, it will be apparent that the swabs or ampoules can be assembled with the bandages in the container in a simple and convenient manner 100 and that this can be accomplished and the container sealed without endangering the swabs or ampoules which necessarily embody a thin friable glass container to hold the iodin or other liquid. This is a very 105 important feature of my invention because if the swab or ampoule should be broken in placing it in the container or in sealing the container it would probably not be discovered until the container was opened to use 110

the bandages in a first aid emergency and by that time the liquid would have escaped from the swab or ampoule.

It will be further understood that changes 5 may be made in my invention within the scope of the appended claims without departing from the spirit thereof or sacrificing any of its material advantages.

I claim:

- 10 1. A first aid packet or package comprising a sealed container, a pair of individual compressed bandages snugly inclosed within said container and provided with complementary depressions in their opposing faces, 15 and a surgical swab disposed in said de-

pressions to permit the container to be sealed without injury thereto.

2. A method of packing bandages and surgical swabs to provide a compact first aid packet or package which consists in 20 subjecting a pair of bandages to pressure to form complementary depressions in their opposing faces, inserting the swabs in said depressions, and inclosing the assembled bandage and swabs in a suitable container. 25

OTTO C. SCHULZ.
